CASEMENT WINDOW AND THE LIKE

Application filed July 7, 1930. Serial No. 465,926.

This invention relates to casement windows, doors and the like, and the objects of the invention primarily are to provide practical and efficient "weathering" and to simplify the mounting of closures of this type in the wall of a building.

The foregoing and other desirable objects are attained in this invention by the novel features of construction, combinations and relations of parts as hereinafter described and broadly covered in the claims.

The drawings accompanying and forming part of the specification illustrate certain practical commercial forms of the invention and it will be understood that the structure may be modified and changed as regards these particular illustrations without departure from the true spirit and broad scope of the invention.

Fig. 1 is an inside view of a complete casement window having features of the invention incorporated therein; Figs. 2, 3 and 4 are enlarged cross-sectional details as on substantially the planes of line 2-2, 3-3 and 4-4 of Fig. 1; Fig. 5 is a similar view as on line 5-5 of Fig. 1, showing only the top and bottom portions of the window structure.

The window chosen for illustration, comprises the two vertically hinged sashes 6, 7, and the upper horizontally pivoted sash 8, Fig. 1, all mounted in a special frame 9 set directly into the masonry or structure of the building wall.

From Figs. 4 and 5, it will be seen that this mounting frame is of hollow channel form open around the outside to bond into the wall, consisting in substance of side flanges 10, 11, connected about the inside of the frame by the portions 12, 13, offset by the intermediate shoulder 14, which faces outwardly of the window to form a contact stop for the sash flange.

At the lower end of the frame, the table 12 may be sloped as shown at the bottom in Fig. 5 to accord with the sill structure.

The frames for the sash 6, 7, 8, are shown as of standard cross-section consisting of a bar portion 15 with a wide outwardly extending flange 16 at the outside of the frame and a narrower outwardly extending sealing

flange 17 at the inside of the frame. The glazing is not shown, but it will be understood that the same is carried in usual fashion by the inwardly extending flange 18, which may be positioned, as shown, for outside glazing or be positioned on bar 15, for inside glazing.

The outside sash flange 16 is intended to abut shoulder 14, the hinges being set to effect this result. This will be particularly clear from Figs. 4 and 5, the first of which shows one of the outwardly offset hinges 19 attached to the outer flange 16, of one of the side sashes at 20, and to the portion 12 of the fixed frame at 21; the second of these views showing at the top, one of the hinges 22 for the upper swinging sash, connected like the other hinges to the outer flanges 16 of the sash at 23 and to the outer portion of the fixed frame 12 at 24.

The upper cross-bar of the frame, indicated generally at 25 and shown in detail in Fig. 2, is constructed in general like the body of the frame, that is at the top with a sill portion 12a, and a table portion 13a connected by stop shoulder 14a and at the bottom with substantially parallel portions 12b, 13b connected by shoulder 14b; similarly as regards the upright intermediate bar 26 of the frame, this having the portions 12c, 13c, connected by the shoulders 14c providing stops for the outer sash flanges 16.

The frame and sash sections are usually of rolled, pressed, drawn, or extruded material and so in the final form have somewhat roughened surfaces, preventing air or weather-tight contact at metal-to-metal joints, such as between sash flanges 16 and the frame shoulders 14.

Weather tight and dust excluding joints between sash and mounting frame are provided in the present invention by a weathering or stop frame set in the mounting frame and adapted to be adjusted to bring a strip of packing material into proper sealing engagement with the sash frame.

This adjustable weathering is shown in each instance as a light frame 27, secured to the inner portion 13 of the main frame by screws 28 passing through slots 29 in the fas-

tening flanges 30 into screw seats 31 in the main frame. These adjustable weathering frames are shown as having open packing channels 32 opening outwardly of the window 5 and carrying strips 33 of felt or other suitable packing material in position for engagement with the packing extensions 17 of the sash frame.

To provide a greater degree of resiliency, 10 facilitate renewal of the packing, etc., the packing strips are shown as elastically and removably held in their channels by spring sheet metal clips or flanges 34 having base portions caught beneath the heads of screws 15 28 and having inwardly angled portions 35 holding the packing strip over in the corner of the packing groove and inclined as indicated to form a dove tail or undercut groove which locks the packing in place. If desired, 20 the packing may be secured in place by glue, cement or other securing medium.

By placing the hinges on the inside, the sash may be made to open inwardly, in which event, it will be understood the parts will be 25 reversed, the weathering frame carrying the packing being then at the outside of the window and the sash swinging inwardly away from the same.

With this invention, it is not necessary to 30 employ special "sub frames" to provide mounting connections between window frames carrying the sash and the building structure.

The present mounting frames 9 serve both 35 as sash framing and as the equivalent of what have been known as the "sub frames" for bonding the window structure in the building wall. Thus, the hollow window frames 9 can be sent out from the factory either with 40 or without the weather stops in place and be set up directly in the building walls ready to receive the hinged sash as soon as building operations have progressed far enough for the hanging of the sash. If any adjustment 45 of the weather stops is necessary to make the packing properly meet the sash, this can be readily accomplished by loosening one or more of the screws 28 and shifting the weather frames until they properly match the sash, 50 after which they are secured in such adjusted relation in the main frame. If the packing becomes worn, the old packing may be readily removed and new packing inserted. The mounting flanges 30 for the weather 55 stops are shown as extending outwardly, so as to be concealed by the sash frame, but it will be understood, that if desired, these mounting flanges might be reversed, that is extended inwardly of the window, so as to 60 leave the adjustable fastenings 28 exposed with the sash in closed position, enabling adjustment of the stops against the sash while the sash is closed. The location of the packing material in a stationary stop frame is 65 preferable to structures where packing ma-

terial is mounted in the edge of the swinging sash, because when such windows are opened, the packing material swings out with the window and is thereby exposed to sun and weather conditions. Another important 70 advantage in providing the weathering in a stop frame separate from the sash is that the sash frame can be made of relatively light section with the fullest area exposed to glazing. The overlap for packing provided by 75 the extension 17 is outside of the glazed portion of the frame and so does not cut down the glazed area.

What is claimed is:

1. In window and door structures, a hollow mounting frame open about the outside for bonding in a wall, said frame having side flanges connected by offset portions which are in turn connected by an intermediate shoulder which is substantially parallel with the side flanges, sash frame or the like having a hinged mounting on one of said relatively offset frame portions and provided with flanges meeting said shoulder part of the frame, weathering interposed between the sash frame and the other relatively offset portion of the mounting frame and means for adjustably mounting said weathering relatively to said offset portion to meet the sash when the flanges of the sash are engaged with 95 said shouldered part of the frame.

2. A casement window, comprising a channel frame for direct mounting in a building wall, said channel frame having side flanges connected by generally parallel portions offset by an intermediate shoulder, a sash frame hinged directly to said mounting frame and having a flange at the outside to engage said shoulder, a weather stop on the mounting frame adjustable to meet the hinged sash frame, said weather stop including a channeled support, packing material in the channel of said support and a spring holding strip resiliently confining said packing in said channel.

3. In a casement window, the combination comprising a shouldered frame, a casement window sash hinged to said frame and having an outer flange engageable with the shoulder of the mounting frame, a channeled member adjustably secured in the mounting frame, packing material in the channel of said adjustable member for engagement with the sash frame of the window and spring clip means for removably and resiliently securing said packing in the channel of the adjustable member.

4. A casement window, comprising a channeled frame having side flanges connected by portions offset by an intermediate shoulder, a window sash hinged in said frame and having an outwardly extending flange for engagement with said shoulder, an inwardly extending glazing flange and a stop flange forming an outwardly projecting continua-

- tion of the glazing flange, a member adjustably secured in the mounting frame and having a channel in back of said stop flange extension and packing in said channel for engagement with said stop flange extension. 5. A casement window, comprising a mounting frame, a sash frame hinged therein, said mounting frame and sash frame having relatively overlapping flange and shoulder portions, a frame adjustably secured in the mounting frame in back of the sash, packing material carried by said adjustably secured frame for engagement with the closed sash frame and screw fastening means between the mounting frame and adjustable packing frame, said screw means being covered by the sash frame when the latter is in closed relation in the mounting frame. 10. A casement window or the like, comprising a mounting frame having a stop shoulder, a sash frame hinged in said mounting frame and having an outstanding flange for engagement with said stop shoulder, a weather stop adjustably secured in the mounting frame, packing material carried by said adjustable weather stop for engagement with the sash frame when the latter is in closed relation with the flange of the same in engagement with the stop shoulder of the mounting frame and yieldable means for resiliently and removably securing said packing in position in the adjustable weather stop. 15. A casement window or the like, comprising a mounting frame having a stop shoulder, a sash frame hinged in said mounting frame and having an outstanding flange for engagement with said stop shoulder, a weathered stop adjustably secured in the mounting frame, packing material carried by said adjustable weather stop for engagement with the sash frame when the latter is in closed relation with the flange of the same in engagement with the stop shoulder and means for securing said weather stop, said securing means being disposed in position covered by the sash frame when the latter is in the closed relation. 20. A casement window or the like, comprising a mounting frame having a stop shoulder, a sash frame hinged in said mounting frame and having an outstanding flange for engagement with said stop shoulder, a weather stop adjustably secured in the mounting frame, packing material carried by said adjustable weather stop for engagement with the sash frame when the latter is in closed relation with the flange of the same in engagement with the stop shoulder, said weather stop being in the form of a frame shiftable transversely in the mounting frame and provided with a transversely slotted securing flange and securing screws engaged with said transversely slotted portions of the weather stop frame. 25. A casement window or the like, comprising in combination, a mounting frame having a shoulder and a sash frame hinged in the mounting frame and having an outstanding flange opposed to the shoulder of the mounting frame in the closed position of the sash, a channel forming member on the mounting frame in back of the outstanding flange of the sash frame and covered by the latter when the sash is closed, securing means for said channel-forming member, said securing means being covered by the sash frame and outstanding flange of the latter when the sash is closed and thereby concealed and protected in the closed position of the sash and packing material held in the channel provided by said channel-forming member in position for sealing engagement with the sash frame in the closed position of the latter. 30. A casement window or the like, comprising in combination, a mounting frame having a shoulder and a sash frame hinged in the mounting frame and having an outstanding flange opposed to the shoulder of the mounting frame in the closed position of the sash, a channel forming member on the mounting frame in back of the outstanding flange of the sash frame and covered by the latter when the sash is closed, securing means for said channel-forming member, said securing means being covered by the sash frame and outstanding flange of the latter when the sash is closed and thereby concealed and protected in the closed position of the sash and packing material held in the channel provided by said channel-forming member in position for sealing engagement with the sash frame in the closed position of the latter. 35. A casement window or the like, comprising in combination, a mounting frame having a shoulder and a sash frame hinged in the mounting frame and having an outstanding flange opposed to the shoulder of the mounting frame in the closed position of the sash, a channel forming member on the mounting frame in back of the outstanding flange of the sash frame and covered by the latter when the sash is closed, securing means for said channel-forming member, said securing means being covered by the sash frame and outstanding flange of the latter when the sash is closed and thereby concealed and protected in the closed position of the sash and packing material held in the channel provided by said channel-forming member in position for sealing engagement with the sash frame in the closed position of the latter, said channel-forming member comprising a strip having an angularly bent edge portion opposed to a part of the mounting frame and cooperating therewith to form the channel undercut to hold the packing material in place. 40. A casement window or the like, comprising in combination, a mounting frame having a shoulder and a sash frame hinged in the mounting frame and having an outstanding flange overlying the shoulder of the mounting frame in the closed position of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position. 45. A casement window or the like, comprising in combination, a mounting frame having a shoulder and a sash frame hinged in the mounting frame and having an outstanding flange overlying the shoulder of the mounting frame in the closed position of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position. 50. A casement window or the like, comprising in combination, a mounting frame having a shoulder and a sash frame hinged in the mounting frame and having an outstanding flange overlying the shoulder of the mounting frame in the closed position of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position. 55. A casement window or the like, comprising in combination, a mounting frame having a shoulder and a sash frame hinged in the mounting frame and having an outstanding flange overlying the shoulder of the mounting frame in the closed position of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position. 60. A casement window or the like, comprising in combination, a mounting frame having a shoulder and a sash frame hinged in the mounting frame and having an outstanding flange overlying the shoulder of the mounting frame in the closed position of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position. 65. A casement window or the like, comprising in combination, a mounting frame having a shoulder and a sash frame hinged in the mounting frame and having an outstanding flange overlying the shoulder of the mounting frame in the closed position of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position.

of the sash, the two frames being arranged with a space between the mounting frame and sash frame in back of said outstanding flange and weathering mounted in said space in back of said sash flange and covered and protected by the latter when the sash is closed, said weathering including a supporting strip and packing medium positioned thereby to form a seal between the mounting frame and sash frame when the latter is in the closed position and screw means for adjustably securing said strip to the mounting frame and positioned to be covered by the sash frame and outstanding flange of the latter when the sash is closed.

13. A casement window or the like, comprising in combination, a hollow mounting frame open about the outside for bonding in a wall, said frame having side flanges connected by offset portions which are in turn connected by an intermediate shoulder, sash frame hinged on one of said relatively offset portions of the mounting frame and provided with an outstanding flange for meeting the shouldered portion of the mounting frame, a weathering support mounted on said mounting frame in back of the stop flange of the sash frame when the latter is closed and weathering medium carried by said weathering support in position to engage the sash frame when the latter is in the closed position.

14. A casement window or the like, comprising in combination, a hollow mounting frame open about the outside for bonding in a wall, said frame having side flanges connected by offset portions which are in turn connected by an intermediate shoulder, sash frame having a hinged mounting on one of said relatively offset portions of the mounting frame and provided with an outstanding flange for meeting said intermediate shoulder of the mounting frame, weathering for sealing the sash frame, a frame structure for supporting said weathering in engagement with an inner portion of the sash frame when the outstanding flange of the latter is engaged with the intermediate shoulder of the mounting frame and means for securing said weathering support to the mounting frame, as aforesaid.

In testimony whereof I affix my signature.
CHARLES L. PETTIT.
